UNITED STATES PATENT OFFICE.

CARL MUELLER, OF SHEBOYGAN, WISCONSIN.

ELEVATOR-BRAKE.

1,249,453.

Specification of Letters Patent. Patented Dec. 11, 1917.

Application filed June 7, 1917. Serial No. 173,343.

To all whom it may concern:

Be it known that I, CARL MUELLER, a citizen of the United States, residing at Sheboygan, in the county of Sheboygan and State of Wisconsin, have invented certain new and useful Improvements in Elevator Brakes; and I do declare the following to be a full, clear, and exact description of the invention, such as will enable others skilled 10 in the art to which it appertains to make and use the same.

My invention relates to that class of devices intended to prevent elevators from dropping in case the raising and lowering 15 cable thereof should break, or if the winding means for said cable should for any reason become injured.

The object of the invention is to provide an extremely simple and inexpensive, yet a 20 highly efficient arrangement of parts for automatically applying a number of gripping dogs to the guide tracks of the elevator, in case of accident, and with this general object in view, the invention resides in 25 the novel features of construction and unique combinations of parts to be herein-after fully described and claimed, the descriptive matter being supplemented by the accompanying drawings which constitute a 30 part of this application and in which:

Figure 1 is a side elevation of an elevator and its guide tracks, showing the application of the invention;

Fig. 2 is an edge view of Fig. 1;

Fig. 3 is a similar view showing the action 35 of parts in case of breakage of the cable;

Fig. 4 is a transverse section on the plane of the line 4—4 of Fig. 1;

Fig. 5 is a similar view on the plane indicated by the line 5—5 of Fig. 1.

In the drawings above briefly described, the numeral 1 designates an elevator platform from which standards 2 rise, said standards being connected at their upper 45 ends by a horizontal bar 3. Suitable guides 4 are provided adjacent the upper and lower ends of the bars 2 for engagement with vertical tracks 5. The parts so far described are typical of one form of elevator commonly used for carrying freight, but it is to be understood that my invention is also applicable to all other kinds of elevator cars and cages.

Bearings 6 are suitably mounted at the 55 upper and lower ends of the elevator and toothed cam-like dogs 7 are pivoted to said

bearings for engagement with the tracks 5 in case of accident to the raising and lowering means of the device, the upper and lower dogs being connected by vertical rods 8 so that they move in unison. Links 9 are 60 pivoted to and rise from the upper dogs 7, the upper ends of said links being pivoted to cross heads 10 on the ends of a horizontal bar 11 which extends above the bar 3, a central load lifting shackle 12 being secured to the center of said bar and receiving the bar 3. The hoisting cable 13 is secured to the upper end of the shackle 12 and since the latter is limited in its upward movement by 70 contact with bar 3, the links 9 and rods 8 are prevented from swinging inwardly beyond dead center (see Fig. 2).

Vertically elongated arched guides 14 are secured at their lower ends to the bar 3 and 75 the ends of bar 11 are mounted in said guides for vertical movement, said ends having vertical openings 15 which receive upstanding guide rods 17 which are positioned in the guides 14 and anchored to the 80 upper ends thereof and to the bar 3. The rods 17 also act as guides for coiled springs 18 which surround said rods and bear against the upper ends of the guides 14 and against the bar 11 to force said bar quickly 85 downward in case the cable 13 should break, or if any other parts of the raising and lowering mechanism should become inoperative.

Whenever bar 11 is depressed by the 90 springs 18, the links 9 rock the upper dogs 7 so as to bring the teeth thereof into engagement with the tracks 5, the lower dogs being similarly rocked by the rods 8. It will thus be obvious that the car is held against 95 falling and thus that injury to the occupants or to the freight on the elevator, will be averted.

The construction shown and described is simple and inexpensive, yet is highly efficient, and it therefore constitutes the preferred form of the improved brake mechanism. I wish it understood, however, that within the scope of the invention as claimed, numerous minor changes may be made without sacrificing the principal advantages.

I claim:

In combination with an elevator, a pair of guide tracks at the opposite ends thereof, a horizontal bar disposed above said elevator 110 having its ends positioned adjacent said tracks, a cable for raising and lowering the

elevator attached to said bar, cross heads on the ends of said bar having depending links, dogs pivoted in bearings extending from the top and bottom of said elevator, said 5 dogs being connected to said links and held from engagement from said tracks by the same, vertically elongated arched guides rising from said elevator and receiving the ends of said bar for vertical movement, 10 means for limiting the upward movement of said bar, vertical rods secured in said guides and passing through openings in said bar,

thereby guiding the movement of the same, and springs surrounding said rods and bearing downwardly on said bar for forcing the 15 same toward the elevator to apply the dogs in case the cable should break.

In testimony whereof I have hereunto set my hand in the presence of two subscribing witnesses.

CARL MUELLER.

Witnesses:

FELIX BENFEY,
EVA BORGERT.
